(57) CLAIM

I claim the ornamental design for a key, as shown and described.

DESCRIPTION

FIG. 1 is a perspective view of a key of the new design; FIG. 2 is a front side view of the key of FIG. 1, FIG. 3 is a rear side view of the key of FIG. 1, FIG. 4 is a top view of the key of FIG. 1; FIG. 5 is a bottom view of the key of FIG. 1; FIG. 6 is a left side view of the key of FIG. 1; and, FIG. 7 is a right side view of the key of FIG. 1. The broken lines, which define the bounds of the claim form no part thereof. The broken lines environmental are for illustrative purpose only and form no part of the claimed design.
